(57) **CLAIM**

The ornamental design for a public lighting fixture, as shown and described.

DESCRIPTION

1. Public lighting fixture

1.1 is a perspective view of a public lighting fixture showing our new design;

1.2 is a front side elevational view thereof;

1.3 is a back elevational view thereof;

1.4 is a left side elevational view thereof;

1.5 is a right side elevational view thereof;

1.6 is a top plan view thereof;

1.7 is a bottom plan view thereof.

The broken lines in the drawings are for the purpose of illustrating portions of the public lighting fixture and form no part of the claim.
